UNITED STATES PATENT OFFICE

122,600

DESIGN FOR AN ELEVATED TANK

George T. Horton, Chicago, Ill.

Application April 27, 1940, Serial No. 92,002

Term of patent 14 years

To all whom it may concern:

Be it known that I, George T. Horton, a citizen of the United States, residing at Chicago, in the county of Cook and State of Illinois, have invented a new, original, and ornamental Design for an Elevated Tank, of which the following is a specification, reference being had to the accompanying drawing, forming a part thereof, in which the figure is a perspective view of an elevated tank showing my new design.

I claim:

The ornamental design for an elevated tank, as shown.

GEORGE T. HORTON.
